FOREIGN PATENT DOCUMENTS

WO DM/058299 * 9/2001
WO DM/068307 * 8/2006*Primary Examiner* — Ian Simmons
Assistant Examiner — Dana L Meyrow(57) **CLAIM**

We claim an ornamental design for a bottle, as shown and described.

DESCRIPTION

FIG. 1 is a top perspective view of a bottle in accordance with our new design.

FIG. 2 is a front elevational view of the bottle in FIG. 1.

FIG. 3 is a top plan view of the bottle in FIGS. 1 and 2, the bottle bottom forming no part of the claimed design.

FIG. 4 is a side elevational view of the bottle in FIGS. 1–3 taken from the right in FIG. 2.

FIG. 5 is side elevational view of the bottle in FIGS. 1–4 taken from the left in FIG. 2; and,

FIG. 6 is a rear elevational view of the bottle in FIGS. 1–5.

1 Claim, 3 Drawing Sheets(56)
